Fig. 4.

UNITED STATES PATENT OFFICE.

ERNST OSCAR NEBEL, OF PHILADELPHIA, PENNSYLVANIA.

LACE ATTACHMENT FOR KNITTING MACHINES.

Application filed November 16, 1921. Serial No. 515,560.

To all whom it may concern:

Be it known that I, ERNST OSCAR NEBEL, a citizen of the United States, residing in Philadelphia, Pennsylvania, have invented 5 certain Improvements in Lace Attachments for Knitting Machines, of which the following is a specification.

The object of my invention is to provide improvements in the lace forming attachments of full fashioned stocking knitting machines whereby the machine may be run at the normal rate of speed during the lace making operation, with a resultant saving of time and increased production.

15 A clear conception of the invention will be obtained from the attached drawings, in which:

Figure 1, is a front elevation of a portion of a full fashioned knitting machine illustrating the essential features of my invention;

Fig. 2, is a front elevation of a portion of the knitting machine illustrating the details of the lace forming mechanism;

25 Fig. 3, is an end elevation of the knitting machine;

Fig. 4, is a plan view of that portion of the knitting machine shown in Fig. 2, and

30 Fig. 5, is a more or less diagrammatic view illustrating the details of the pattern chain.

With reference to the drawings, 1 indicates the frame of a full fashioned stocking knitting machine, 2 the knitting head, and 3 the lace finger which carries needles 4, the said finger being carried by a rod 5 mounted for reciprocation upon the oscillating frame 6. The rod 5 receives the forward movement of its reciprocation through the 35 medium of a downwardly extending arm 7 of a slide 8 mounted in a guide 9 suitably secured to the said frame 1, said slide 8 being reciprocated in the guide 9 by means of a pusher lever 10 pivotally mounted upon the frame 1, which in turn is actuated by a rod 11, whose upper end abuts the under side of said lever 10, and whose lower end is pivotally attached at 12^a to a rock lever 12 intermediate its free end and the opposite end 45 thereof which is pivotally mounted upon a fixed shaft 13, the said lever receiving an oscillatory motion through a cam 14 upon the cam shaft 15, which cam 14 engages a cam roller 16 upon the said lever 12.

50 The rearward travel of the shaft 5 is effected by means of a spring 17, one end of

which is attached in suitable manner to the relatively fixed shaft 18, while the other end is connected by means of a bracket 19 to the said rod 5. The rod 5 has in the end 60 thereof a screw 5^a, the head of which abuts the said arm 7, said screw providing means for adjusting the rod 5 relative to the arm.

Pivotedly mounted upon an eccentric shaft 20 carried in suitable bearings 21 upon the 65 frame 1, are a series of selector arms 22, the forward ends of said arms being supported by a corresponding series of coiled springs 23 which depend from an arm 74 upon an upright 75 upon the said frame 1. The ends 70 of the said selector arms lie adjacent the inner end of the slide 8, and each of said arms has extending from the end thereof a set of selector fingers, 24, of differing 75 lengths, the ends of these fingers being engaged by the said inner end of the slide 8, the rearward motion of said slide being thereby limited according to the particular finger which it engages. At the same time, the arm 22, through the rotation of the eccentric shaft 20, is given a substantially 80 horizontal reciprocatory motion which is communicated to the needle finger 3 through the slide 8 and the shaft 5, in the manner previously described.

The position of the arm 22 and the particular selective finger which is to be engaged by the slide 8 is determined by means of a pattern chain 25, having extending from the face thereof pattern members or buttons 26, which, when they lie in a vertical position at the lowest point of the chain, are adapted to engage the upper surface of the arm 22, thereby holding the arm against the tension of the spring 23 in a given position, 90 presenting one or other of the selector fingers to the end of the slide 8, according to the length of the pattern member which happens to lie in engagement with the said arm. 95

A pair of sprocket wheels 27, upon which 100 the lower end of the pattern chain 25 rides, is mounted in the present instance upon an oscillatory bar 28, said bar being pivotally secured at one end to an upright 29 upon the frame 1, and having attached to its free end the upper extremity of a reach rod 30, which connects the said arm to a rock lever 31 pivotally mounted upon the fixed shaft 13 and having upon the free end thereof a cam roller 32 which lies in engagement with 105 a cam 33 upon the said cam shaft 15. Through the cam 33, the bar 28 receives a 110

vertical oscillatory motion which carries the sprockets 27 and the chain 25 upwardly so that the pattern fingers 26 are elevated clear of the selector arm 22, thereby permitting 5 the turning of the chain and the bringing of another pattern finger into position to engage the said arm 22 when the bar 28 is carried downwardly to the normal position. In order to permit the pattern pins 26 to be 10 elevated clear of the arm 22, a stop 34 is provided which overlies the said selector arms 22 and limits their upward motion.

In order that the pattern chain may move upwardly with the sprockets 27 and remain 15 continuously in engagement therewith, the device illustrated in Fig. 5 is employed. The chain passes over the pulleys 35 and 36 and around the pulley 37, the pulleys 35 and 36 being suspended from a suitable 20 bracket 38 upon the upright 29 and the pulley 37 being attached to the said bracket through the medium of a coil spring 40 in the manner clearly illustrated. With this arrangement, the vertical motion of the 25 sprocket 27 is equalized by the tension of the spring 40 and the chain is always retained taut. The rotary motion of the sprocket 27 by means of which the chain is actuated to bring the desired pattern fingers 30 into engagement with the arm 22 is accomplished by means of a ratchet wheel 41 upon a shaft 42 which carries the sprockets 27, said ratchet wheel being engaged by a pawl 43 carried by a lever arm 44, one end of 35 which is pivotally secured at 45 to the frame 1, said lever 44 being connected by means of a reach rod 46 to a rock lever 47 mounted upon the fixed shaft 13, the forward end of which rock lever lies in engagement with a 40 cam 48 upon the cam shaft 15. A spring 49 secured to the pawl 43 and to the arm 44 exerts a force tending to retain the pawl against the face of the ratchet wheel 41.

The horizontal motion previously mentioned of the arm 22 may be in either direction, the direction of the motion of the said arms 22 depending upon the direction of rotation of the eccentric shaft 20. This shaft 20 receives its motion in one direction 50 through a rocker arm 50 secured to one end thereof, said rocker arm having attached thereto a reach rod 51, the lower end of which is secured to a rock arm 52 mounted upon the fixed shaft 13 and carrying a cam 55 roller 53 which lies in engagement with a cam 54 upon the cam shaft 15. The oscillation of the shaft 20 in the opposite direction is obtained by the following mechanism: Secured in the outermost of the 55 selector arms 22 is a set screw 55, the bottom of said set screw being adapted to bear against one arm 56 of a lever 57 pivotally secured at 58 to the frame 1, the lower arm 56^a of said lever extending downwardly and 60 normally bearing against a pin 59 which

extends laterally from an arm 60 pivotally secured to a pin 61^a at the forward end of a rock lever 61 mounted upon the fixed shaft 13, said rock lever 61 also having a cam roller 62 secured thereto which lies in engagement with a cam face 63 upon the cam shaft 15. The arm 56^a of the lever 57 and consequently the lever 60 is held in a normal position in which they are shown in Fig. 2 by a spring 64, one end of which is attached to the said arm 56^a and the other to the frame 1, while a spring 65 of lesser strength than spring 64 attached to the said arm 60 has the opposite end thereof secured to a fixed arm 66 and exerts a pressure opposite to the pressure of the spring 64 whereby the said arm 60 is retained in a position with the pin 59 bearing against the arm 56^a.

Suitably positioned upon the rod 51 is an adjustable lug 67, under which the pin 59 under certain conditions is adapted to lie so that any upward movement of the said arm 60 due to the action of the cam 63 may be transmitted through the said lug 67 to the rod 51, and so to the shaft 20. This shifting of the elements to cause the pin 59 to underlie the lug 67 is effected by means of one series of the pattern fingers 26, said fingers at the proper intervals being brought into position to engage the said outermost arm 22 which carries the said set screw 55, whereby the said arm is forced downwardly, causing the set screw 55 to bear against the upper surface of the arm 56, thereby causing the arm 56^a to be shifted so as to permit the arm 60 to move under the action of the spring 65 toward the rod 51, said rod at the moment being elevated to permit the pin 59 to pass underneath the lug 67.

Suitable means is provided for retracting the pawl 43 from engagement with the ratchet wheel 41 whereby further movement of the pattern chain is prevented, said retracting means consisting in the present instance of a link 68 attached to the said pawl and having a recess or notch 69 adapted to lie over and engage a pin 70 secured to the said frame 1, whereby the pawl is held away from the ratchet. Means is also provided for relieving the upward tension of the springs 23 upon the arms 22, the arm 74 being pivotally mounted to the upright 75 at 71, and being held in the normal elevated position in which the spring is caused to elevate the arms 22 by means of an adjustable detent 72, which latter when turned at an angle of 90° to the normal position permits the depression of the arm 74 and consequently of the selector arms 22.

The operation of the device will be apparent to those skilled in the art. In the present forms of lace-forming attachments of this type, it is the custom instead of elevating the pattern chain, to depress the selector 130

arms 22 in order to permit the chain to be shifted to bring a new selector pin into position. This system has the serious drawback of necessitating the slowing down of the machine from the normal speed in order to allow sufficient intervals of time for the movement of the arm 22, which must be comparatively great. If it is attempted to speed up the machine, the inevitable result 10 is a racking of the parts which causes unwarranted wear upon the various parts and an inevitable loosening thereof which eventually gives rise to various irregularities in the formation of the lace. By elevating the 15 pattern chain in the manner herein described I am able to make the necessary changes in the pattern pins and to return the various parts to their proper operating positions with much less motion and consequently in 20 much faster time, so that it is possible to run the machine in any lace forming operation at the regular normal speed employed in knitting an ordinary stocking.

I claim:

25 1. In a knitting machine, the combination with a movable lace finger having needles adapted for cooperation with the knitting needles to form a lace design in the knitted fabric, means for reciprocating said finger 30 toward and from the knitting needles, and mechanism for reciprocating said finger longitudinally of the row of knitting needles comprising an adjustable member having a 35 plurality of means individually operative in different adjusted positions of the member for positioning the said finger longitudinally of the row of knitting needles, mechanism for reciprocating said member, and variable 40 means adapted for reciprocation with respect to said member for determining the adjusted position of the latter.

2. In a knitting machine, the combination with a movable lace finger having needles adapted for cooperation with the knitting 45 needles to form a lace design in the knitted fabric, means for reciprocating said finger toward and from the knitting needles, and mechanism for reciprocating said finger longitudinally of the row of knitting needles comprising an adjustable member having a 50 plurality of means individually operative in different adjusted positions of the member for positioning said finger longitudinally of the row of knitting needles, mechanism 55 for reciprocating said member, a pattern chain having elements adapted to engage and to determine the adjusted position of said member, mechanism for actuating the chain to advance said elements successively 60 into member-engaging position, and means for shifting the chain to disengage said elements from said member during the element-advancing operations.

3. In a knitting machine, the combination 65 with a movable lace finger having needles

adapted for cooperation with the knitting needles to form a lace design in the knitted fabric, means for reciprocating said finger toward and from the knitting needles, and mechanism for reciprocating said finger 70 longitudinally of the row of knitting needles comprising an adjustable member having a plurality of means individually operative in different adjusted positions of the member for positioning said finger longitudinally of the row of knitting needles, mechanism for reciprocating said member, a pattern chain having elements adapted to engage 75 said member, means tending to retain the member in engagement with said elements, means limiting the movement of said member toward the chain, mechanism for actuating said chain to advance the said elements consecutively into position for engaging 80 said member, and mechanism for shifting said chain to disengage said elements from the member during the element-advancing operations.

4. In a knitting machine, the combination with a movable lace finger having needles 90 adapted for cooperation with the knitting needles to form a lace design in the knitted fabric, means for reciprocating said finger toward and from the knitting needles, and mechanism for reciprocating said finger longitudinally of a row of knitting needles 95 comprising an adjustable member having a plurality of means individually operative in different adjusted positions of the member for positioning said finger longitudinally of the row of knitting needles, mechanism for reciprocating said member, a pattern chain having pattern elements adapted to engage 100 said member, a sprocket for said chain, chain actuating mechanism whereby said elements are advanced consecutively 105 into position to engage said member, a support for said sprocket, and mechanism for shifting said support to disengage the said elements from said member during actuation 110 of the chain.

5. In a knitting machine, the combination with a movable lace finger having needles 115 adapted for cooperation with the knitting needles to form a lace design in the knitted fabric, means for reciprocating said finger toward and from the knitting needles, and mechanism for reciprocating said finger longitudinally of the row of knitting needles comprising an adjustable member having a 120 plurality of means individually operative in different adjusted positions of the member for positioning said finger longitudinally of the row of knitting needles, mechanism for reciprocating said member, a pattern chain, a sprocket for said chain, a movable support for said sprocket, pattern elements upon the chain adapted when the sprocket is in the normal position to engage said member, means tending to retain the member 125 130

in engagement with said elements, means limiting the movement of the member toward the chain, mechanism for actuating said chain to advance the said elements consecutively into position to engage said member, and mechanism for shifting the movable sprocket support to shift the said sprocket from the normal position and to thereby disengage the pattern elements from 10 the selector member during actuation of the chain.

6. In a knitting machine, the combination with a movable lace finger having needles adapted for cooperation with the knitting 15 needles to form a lace design in the knitted fabric, means for reciprocating the finger toward and from the knitting needles, and mechanism for reciprocating said finger longitudinally of the row of knitting needles 20 comprising a plurality of adjustable members having each a plurality of means individually operative in different adjusted positions of the members for positioning the said finger longitudinally of the row of knitting 25 needles, mechanism for reciprocating said members, a pattern chain having elements adapted to engage said members, mechanism for operating said chain to advance the elements consecutively into positions to engage 30 said members, and means for shifting the chain to disengage the said elements from the members during the element-advancing operations.

7. In a knitting machine, the combination 35 with a movable lace finger having needles adapted for cooperation with the knitting needles to form a lace design in the knitted fabric, means for reciprocating said finger toward and from the knitting needles, and 40 mechanism for reciprocating said finger longitudinally of the row of knitting needles comprising an adjustable member having a plurality of means individually operative in different adjusted positions of the member 45 for positioning said finger longitudinally of the row of knitting needles, mechanism for reciprocating said member, a pattern chain having pattern elements adapted to engage said member and to hold the latter in given 50 positions, a spring tending to retain said member in engagement with the pattern elements, a stop limiting the movement of the member toward the chain, mechanism for actuating said chain to advance the elements 55 successively into a position to engage said member, and means for shifting the chain to disengage the elements from said member during actuation of the chain.

8. In a knitting machine, the combination 60 with a movable lace finger having needles adapted for cooperation with the knitting needles to form a lace design in the knitted fabric, means for reciprocating said finger toward and from the knitting needles, 65 and mechanism for reciprocating said finger

longitudinally of the row of knitting needles comprising an adjustable member having a plurality of means individually operative in different adjusted positions of the member for positioning said finger longitudinally of the row of knitting needles, mechanism for reciprocating said member, a pattern chain having pattern elements adapted to engage said member, mechanism for actuating the chain to bring said elements successively into position to engage the member, and mechanism for shifting said chain to disengage the elements from said member during actuation of the chain to bring an element into member-engaging position and for returning said chain to bring the said elements into engagement with the member after the said advancing operations.

9. In a knitting machine, the combination 85 with a movable lace finger having needles adapted for cooperation with the knitting needles to form a lace design in the knitted fabric, means for reciprocating said finger toward and from the knitting needles, and mechanism for reciprocating said finger longitudinally of the row of knitting needles comprising an adjustable member having a plurality of means individually operative in different adjusted positions of the member for positioning said finger longitudinally of the row of knitting needles, mechanism for reciprocating said member, a pattern chain having pattern elements adapted to engage said member, a sprocket for said chain, mechanism for actuating said chain to bring the elements successively into position to engage said member, mechanism for shifting the sprocket to disengage the pattern elements from said member during actuation of the chain, and means operatively associated with said chain for retaining the latter continuously in engagement with the sprocket.

10. In lace forming mechanism for knitting machines, the combination with a reciprocating lace finger, of mechanism for actuating said finger comprising a movable selector element, a pattern chain having pattern members adapted to engage said element, a sprocket for said chain, mechanism for actuating said chain to bring said members consecutively into position to engage said element, mechanism for shifting the sprocket to disengage the pattern members from said element during actuation of said chain, and means operatively associated with said chain and including a spring tending to exert a pull upon said chain in opposition to said sprocket for retaining said chain continuously in engagement with said sprocket.

11. In a knitting machine, the combination 125 with a movable lace finger having needles adapted for cooperation with the knit-

ting needles to form a lace design in the knitted fabric, means for reciprocating said finger toward and from the knitting needles, and mechanism for reciprocating said finger longitudinally of the row of knitting needles comprising an adjustable member having a plurality of means individually operative in different adjusted positions of the member for positioning said finger longitudinally of the row of knitting needles, mechanism for reciprocating said member, a sprocket movably mounted above the said member, a pattern chain meshing with the sprocket and having pattern elements adapted to engage said member, said chain extending upwardly from the sprocket, resilient means operating on the chain to hold it tight on the sprocket, mechanism for rotating the sprocket to bring the said pattern elements successively into position to engage said member, and mechanism for reciprocating the sprocket to engage and disengage the pattern elements with and from said member during rotation of the sprocket.

5 with a movable lace finger having needles adapted for cooperation with the knitting needles to form a lace design in the knitted fabric, means for reciprocating the finger toward and from said knitting needles, and mechanism for reciprocating said finger longitudinally of the row of knitting needles comprising a relatively fixed eccentric rock shaft, a member journaled on said shaft and having a plurality of means individually operative in different adjusted positions of the member around the shaft for positioning said finger longitudinally of the row of knitting needles, mechanism for 10 rocking said eccentric shaft to reciprocate said member, a pattern chain having elements adapted to engage and to determine the adjusted position of said member, mechanism for actuating the chain to advance 15 said elements successively into member-engaging position, and means for shifting the chain to disengage said elements from said member during the element-advancing operations.
